UNITED STATES PATENT OFFICE.

HARRY S. HART, OF CHICAGO, ILLINOIS.

LOCKING MECHANISM FOR CAR-DOORS.

1,308,418.

Specification of Letters Patent.

Patented July 1, 1919.

Application filed October 25, 1917. Serial No. 198,384.

To all whom it may concern:

Be it known that I, HARRY S. HART, a citizen of the United States, and resident of Chicago, in the county of Cook and State 5 of Illinois, have invented certain new and useful Improvements in Locking Mechanism for Car-Doors, of which the following is a specification.

This invention relates to railway cars, and 10 more particularly to locking mechanism for the doors of such cars.

One of the objects of the invention is to make it necessary to close or actuate a given door of a railway car a predetermined 15 amount before a second given door can be closed or actuated a predetermined amount.

Another object is to make certain that doors in the floor of a freight car are closed for the safe passage of merchandise and 20 cattle before the side doors of the car are closed.

These and other objects are accomplished by providing, in a railway car, the combination of a plurality of car doors located in 25 different parts of the car, and means whereby said doors must be closed in a given sequence.

The invention is illustrated on the accompanying sheets of drawings, in which—

30 Figure 1 is a fragmentary side elevation of a freight car embodying my invention; and,

Fig. 2 is a fragmentary sectional view of the same showing one of the floor doors 35 closed and another of the floor doors opened, with the locking mechanism in each case being in a corresponding position.

The various novel features of my invention will be apparent from the following 40 description and drawings and will be particularly pointed out in the appended claims.

This invention has particular reference to that type of railway freight car which has doors in its floor and also at the sides, where- 45 by the car not only may be used for carrying various kinds of material which may be dumped by operating the doors, but also a car which is suitable for carrying cattle and the like, in which case it is necessary that 50 the drop doors be positively locked in their upper or closed position. If these drop doors in the floor of the car are raised to their full closed position before the side doors are closed, it is rather safe to assume 55 that these drop doors will not accidentally move into an opened position to dump the

merchandise or cattle onto the tracks. Therefore, I have provided means whereby it is necessary to move the doors in the floor of the car into their raised or closed position 60 before the side doors may be closed.

By referring to the figures of the drawings, it will be noted that I have shown a freight car 10 having center sill members 11 and side sill members 12, which respectively 65 support portions of the floor 13 and the sides 14, including the side stakes 15. Suitably pivotally connected to the floor structure of the car are a plurality of drop doors 16 and 17, respectively mounted on opposite sides of 70 the center line of the car. These doors form a portion of the floor of the car and normally are retained in a raised position by operating shafts 18, which carry disks 19 engageable with a metal band 20 secured to 75 the under part of the drop doors. As shown in the left-hand half of Fig. 2, the disk 19 is engaging the lowest point of the strap 20 to hold the door 16 in its elevated position. The shaft 18 is laterally movable in an elongated slot 21 in a transversely extending frame member 22 of the car. The shaft 18 may be actuated in either direction by any suitable means. When the shaft 18 is in a 80 position to hold the drop doors in their closed position, said shaft 18 engages the lower end of a lever 23, which is pivoted intermediate its ends to a casting 24 secured to the side sill 12. Pivotally connected to the upper end of the lever 23 by a loose joint 85 is a pin 25 which extends laterally through an opening in the side sill structure. Interposed between the lower end of the lever 23 and a casting 26 on the side sill, is a resilient member or spring 27 which is retained in 90 position by co-operating retaining lugs 28 and 29 and which normally tends to press the lower end of the lever toward the center of the car, thereby tending to press the pin 25 outwardly to project the outer end of the 100 pin 25 into the path of movement of a casting 30 secured to one lower corner of the side door 31. The side door, in each case, is actuated in its sliding movement longitudinally with respect to the car on a rod 36 105 which is embraced by the casting 30, and a roller 32 carried in the casting rides upon the guide rod 36. As stated before, in the left half of Fig. 2, the operating shaft 18 is shown in a position to hold the drop door 110 16 in its raised or closed position, in which case the shaft 18 also is pressed against the

lower part of the lever 23 with the necessary force to overcome the compressive strength of the spring 27 to draw the pin 25 inwardly beyond the path of movement of the casting 30 on side door 31. When the drop doors 16 are raised and the operating shaft 18 is in its supporting position, the side door 31 may be moved from its extreme open position to its extreme closed position, and under these circumstances, if it is possible to move the side door from its extreme open position to its extreme closed position, it is certain that the drop doors are closed on that side of the car to insure safe transit of live stock.

15 By referring to the right-hand half of Fig. 2, it will be noted that the operating shaft 33 has been moved to its inner position, whereupon the drop doors on that side of the car were free to move into their lower or open position. Under such circumstances, the spring 34 presses the pin 35 outwardly to prevent the side door from moving from an open position to a closed position. To raise the drop doors 17 into their closed position, it is merely necessary to actuate the operating shaft 33 to its outward limit of movement, whereupon the drop doors 17 will be held positively in their closed positions and the pin 35 will be withdrawn from the path of movement of the other side door 37. This side door, then, may be closed. In this way live stock may be insured safe transportation.

It is apparent that there may be modifications of the invention as herein particularly shown and described, and it is my intention to cover all such modifications which do not involve a departure from the spirit and scope of the invention as set forth in the following claims.

I claim:

1. In a railway car, the combination of a movably mounted door in the floor of the car, a side door, and means whereby the door in the floor of the car must be closed before the side door can be closed.
2. In a railway car, the combination of a movably mounted door in the floor of the car, a side door, and means associated with said doors whereby the door in the floor of the car must be closed before the side door can be closed.
3. In a railway car, the combination of a plurality of movably mounted doors located in different parts of the car, and means whereby one of said doors must be closed before another of said doors can be closed.
4. In a railway car, the combination of a plurality of movably mounted doors in different parts of the car, and means associated

with said doors whereby one of said doors must be closed before another of said doors can be closed.

5. In a railway car, the combination of a plurality of car doors located in different parts of the car, and means whereby the same must be closed in a given sequence.

6. In a railway car, the combination of a plurality of car doors located in different parts of the car, and means associated with said doors whereby the same must be closed in a given sequence.

7. In a railway car, the combination of a plurality of movably mounted doors located in different parts of the car, and means whereby one of said doors must be moved to a closed position before another of said doors can be moved from one extreme position to another.

8. In a railway car, the combination of a plurality of movably mounted doors located in different parts of the car, and means whereby one of said doors must be actuated a predetermined amount before another of said doors can be actuated a predetermined amount.

9. In a railway car, the combination of a movably mounted door in the floor of the car, a side door for said car, and means whereby the floor door must be moved into a position to sustain a load in the car before the side door can be closed.

10. In a railway car, the combination of a plurality of movably mounted doors located in different parts of the car, and means whereby it is necessary for one of said doors to be actuated a predetermined amount before another of said doors may be actuated a predetermined amount.

11. In a railway car, a movably mounted door in the floor of the car, a side door for the car, an operating shaft, normally supporting the floor door in its closed position, and means controlled by said operating shaft whereby the side door can be closed only after the shaft has moved into a position to support the door in the floor of the car.

12. In a railway car, the combination of a movably mounted door in the floor of the car, an operating shaft normally sustaining the door in its closed position, a side door for the car, a lever, and a member connected to said lever, said lever being controlled by said operating shaft whereby the member may permit or prevent a predetermined movement of the side door.

Signed at Chicago, Illinois, this 17th day of October, 1917.

HARRY S. HART.
